UNITED STATES PATENT OFFICE.

SEATON K. MILLIGAN, OF CHICAGO, ILLINOIS, ASSIGNOR TO AMALGAMATED ROOFING COMPANY, OF CHICAGO, ILLINOIS, A CORPORATION OF ILLINOIS.

ROOFING.

Application filed October 18, 1924, Serial No. 744,377. Renewed December 24, 1926.

- My invention relates to improvements in roofing, and is particularly concerned with improvements in roofing of the so-called "prepared" type.
- 5 The objects of my present invention are: First, to provide a roofing of prepared roofing material in which the light and shadow effect of a wood shingle roof is approximated, or even intensified;
- 10 Second, to provide a roofing of prepared roofing material that is not flat or monotonous in appearance and in which the shingles are arranged so that they will not produce the "pattern" effect common to many roofs formed of prepared roofing;
- 15 Third, to provide a roof in which the butts of the shingles appear to be much thicker than they are, thereby producing the illusion of the light and shadow effect;
- 20 Fourth, to provide roofing, of the character described, that is simple in construction, economical to manufacture and easy to apply; and
- 25 Finally, to provide a novel means for producing roofing of the character described above.
- Other objects of my invention will appear as this description progresses, reference being had to the accompanying drawings in
- 30 which:
- Figure 1 is a side elevation of a roof embodying my invention;
- Figure 2 is a perspective view of one of the shingles used for producing the roofing shown in Figure 1;
- 35 Figure 3 is a perspective view of a modified form of shingle;
- Figure 4 is a similar view of another modified form of shingle; and
- 40 Figure 5 is an elevation of a portion of a roof embodying still another modification of my invention.
- Referring to the drawings, my improved roof comprises a suitable foundation 10 of
- 45 sheathing, or other material, upon which the shingles are arranged in overlapping courses, with the shingles of each course overlapping the joints of the next lower course, as shown in Figure 1. The butt ends of the shingles in each course are staggered
- 50 with relation to each other, so as to tend to break up any tendency to form a pattern. This staggering may be uniform, as shown in the drawings, or the distances that the
- 55 shingles are offset, relatively to each other,
- may be varied so as more completely to effect this result.
- Underlying each top shingle 11 is a second shingle 12, the butt end of which extends slightly downwardly beyond the butt end of the top shingle. Preferably, the exposed end portion of the underlying shingle is black, or some other dark color.
- I prefer to have the exposed surfaces of the upper shingles covered with colored grits, or other suitable surfacing material. In the preferred embodiment of my invention these colored grits, or the surfacing material, should be lighter in color than the exposed end portion of the lower shingle. I find that shingles, such as described in my co-pending application, Serial No. 718,830, filed June 9, 1924, are admirably adapted for this use.
- The underlying shingle not only adds to the thickness of the upper shingle, but when the roof is observed from a distance, the exposed portion of the lower shingle has the effect of increasing the apparent thickness of the upper shingle, so that the observer, in place of seeing two shingles or parts thereof, appears to see a single shingle, the butt of which is of very considerable thickness. It will, of course, be understood that the effect produced by the protruding end of the lower shingle can be increased or decreased, if desired, by permitting more or less of the lower shingle to project beyond the upper one.
- I prefer to make the two shingles 11 and 12 separate from each other and to superimpose them, as shown, when the roof is laid. These shingles may, however, be cemented, or otherwise secured together, as desired, so that they can be laid as a single unit.
- That form of my invention shown in Figure 3 is similar to that of Figure 2, except that the underlying shingle is somewhat shorter than the upper one, being just long enough to receive the nail that passes through the upper shingle.
- In that form of my invention shown in Figure 4, I contemplate securing to the butt end of the upper shingle a very much shorter shingle or strip 12', so that a single unit will be produced that will give the same effect as the double shingle of Figures 2 and 3.
- That form of my invention shown in Figure 5 contemplates making use of a strip 13 of roofing material that has notches
- 14
- 110

- cut in one side at regular intervals, so as to produce projections 15, alternating with the notches. The notches 14 and the projections 15 are of substantially the same width and equal in width to the shingles 11 that are shown in dot and dash, superimposed upon the strip in such manner as to expose the notched edge of the strip sufficiently to produce the same effect as that produced by the projecting ends of the lower shingles in Figures 1 to 4, inclusive. A roof built up in the manner shown in Figure 5 will have substantially the same appearance as that of Figure 1 and the added advantage that the strip 13 covers the joints between adjacent shingles in the next lower course.

It is comparatively an easy matter to make a roof in accordance with my invention, as described above, and a roof thus constructed does not have the flat appearance of a roof constructed with a single layer of shingles made from prepared roofing, nor does it have the same monotonous appearance of similar roofs in which the shingles are laid in such manner as to produce a large number of patterns or designs of similar outline.

While I have described the details of construction of the preferred embodiments of my invention, it is to be clearly understood that my invention is not limited to these details, but is capable of other adaptations and modifications within the scope of the appended claims.

Having thus described my invention, what I claim is:

1. A roof comprising a plurality of overlapping courses of shingles, the shingles of each course covering the joints between the adjacent shingles of the next lower course, and having their butt ends staggered with relation to the butt ends of the adjacent shingles in the same course, and a second shingle lying beneath each of said shingles and projecting beyond the butt end thereof a sufficient distance to produce an impression of thickness but not appearing as a separate shingle, the projecting portions of said lower shingles being dark in color, each of said second shingles being of substantially the same width as the shingle above it.

2. A roof comprising a plurality of overlapping courses of shingles, the shingles of each course covering the joints between the adjacent shingles of the next lower course,

and a second shingle lying beneath each of said shingles and projecting beyond the butt end thereof a sufficient distance to produce an impression of thickness but not appearing as a separate shingle, the projecting portions of said lower shingles being dark in color, each of said second shingles being of substantially the same width as the shingle above it.

3. A roof comprising a plurality of overlapping courses of laterally abutting shingles, having the butt ends arranged in staggered relation and a strip of roofing material projecting substantially uniformly beyond the butt end of each shingle, the projecting portion of said strip being darker in color than said shingle.

4. An article of manufacture comprising a shingle of prepared roofing material and a strip of roofing material secured to the butt end of said shingle and projecting therebeyond, the outer surface of the projecting portion of said strip being different in color from the color of said shingle.

5. Applied roofing comprising a plurality of overlapping flexible shingle pieces, each shingle piece having an exposed lower edge, and other pieces underlying and supporting said lower shingle piece edges, said other pieces being of different color than the shingle piece edges they support and projecting out from under said shingle piece edges, the lower edges of said other pieces conforming in contour to the lower shingle piece edges supported thereby, whereby an individual shadow effect is produced for each shingle piece.

6. Applied roofing comprising a plurality of overlapping flexible shingle pieces, each shingle piece having an exposed lower edge, and another individual lower piece underlying and supporting the lower edge of each of said shingle pieces, said other pieces being of different color than the shingle piece edges they support and projecting out from under said shingle piece edges, the lower edges of said other pieces conforming in contour to the lower shingle piece edges supported thereby, whereby an individual shadow effect is produced for each shingle piece.

In witness whereof, I hereunto subscribe my name this 8th day of October, 1924.

SEATON K. MILLIGAN.
